(57) **CLAIM**

The ornamental design for a shoe cleaning device, as shown and described.

DESCRIPTION

FIG. 1 is a top, front, side perspective view of a shoe cleaning device showing my design.

FIG. 2 is an exploded view of the shoe cleaning device of FIG. 1.

FIG. 3 is a top, front, side perspective view of the shoe cleaning device depicted in FIG. 1 in an alternate configuration.

FIG. 4 is a right side view of the shoe cleaning device.

FIG. 5 is a back view of the shoe cleaning device.

FIG. 6 is a left side view of the shoe cleaning device.

FIG. 7 is a front view of the shoe cleaning device.

FIG. 8 is a top view of the shoe cleaning device.

FIG. 9 is a bottom view of the shoe cleaning device.

FIG. 10 is an isometric bottom view of a Handle/Nozzle Portion of the shoe cleaning device; and,

FIG. 11 is a perspective view of the shoe cleaning device shown in an environment of use thereof.

The broken lines shown in the drawings are included for the purposes of illustrating environmental structure and form no part of the claimed design.

1 Claim, 11 Drawing Sheets
